CLAIM

The ornamental design for an input device for integrating a physical and virtual interface, as shown and described.

DESCRIPTION

FIG. 1 is a perspective view of an input device for integrating a physical and virtual interface showing my new design; FIG. 2 is a perspective view thereof; FIG. 3 is a top plan view thereof; FIG. 4 is a bottom plan view thereof; FIG. 5 is a front elevational view thereof; FIG. 6 is a rear elevational view thereof; FIG. 7 is a left side elevational view thereof; and, FIG. 8 is a right side elevational view thereof.

The broken lines illustrate portions of the input device for integrating a physical and virtual interface which form no part of the claimed design.
